[57] **CLAIM**

The ornamental design for a separable container for flowers, shrubs, or the like, as shown and described.

DESCRIPTION

FIG. 1 is a front elevational view of the separable container for flowers, shrubs or the like showing my new design, the rear being a mirror image thereof;
FIG. 2 is a side elevational view of FIG. 1, the side opposite being identical;

FIG. 3 is a top plan view of FIG. 1;

FIG. 4 is a front elevational view of a second embodiment of the design of FIG. 1, the only difference being the base section.

The bottom of both embodiments is flat and unornamented.
